Primary Examiner — Clare E Heflin(57) **CLAIM**

The ornamental design for a lawn light, as shown and described.

DESCRIPTION

FIG. 1 is a perspective view of a lawn light showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of the lawn light taken from the circle part in FIG. 1.

The broken lines shown on the drawings depict portions of the lawn light that form no part of the claimed design.
